US00D733115S

(12) **United States Design Patent**
Aspinall et al.

(10) **Patent No.:** US D733,115 S
(45) **Date of Patent:** ** Jun. 30, 2015

(54) **MOBILE HOLDER**

(71) Applicant: **IOTTIE, INC.**, Hackensack, NJ (US)

(72) Inventors: **John Aspinall**, Staten Island, NY (US);
James Byun, Brooklyn, NY (US); **Kyu Seop Lee**, Basking Ridge, NJ (US); **Alan Yu Tung Ng**, New York, NY (US)

(73) Assignee: **IOTTIE, INC.**, Hackensack, NJ (US)

(**) Term: **14 Years**

(21) Appl. No.: **29/507,974**

(22) Filed: **Oct. 31, 2014**

(57) **CLAIM**
The ornamental design for mobile holder, as shown and described.

DESCRIPTION

FIG. 1 is a perspective view of the top, front, and right side of the mobile holder of the present invention;

FIG. 2 is a perspective view of the top, rear, and right side of the mobile holder of FIG. 1;

FIG. 3 is a perspective view of a front and a right side of the mobile holder of FIG. 1;

FIG. 4 is a perspective view of a front and a left side of the mobile holder of FIG. 1;

FIG. 5 is a side view of the left side of the mobile holder of FIG. 1;

FIG. 6 is a front view of the mobile holder of FIG. 1;

FIG. 7 is a top view of the mobile holder of FIG. 1;

FIG. 8 is a rear view of the mobile holder of FIG. 1;

FIG. 9 is a side view of the right side of the mobile holder of FIG. 1;

FIG. 10 is a bottom view of the mobile holder of FIG. 1;

FIG. 11 is a front view of the holder of FIG. 1 with side arms extended;

FIG. 12 is a perspective view of the top, front, and right side of the mobile holder of FIG. 1 with side arms extended;

FIG. 13 is a perspective view of the top, front, and right side of the mobile holder of FIG. 1 shown in an environment of use; and,

FIG. 14 is a perspective view of the top, rear, and right side of the mobile holder of FIG. 1 shown in an environment of use.

The broken line showing of the mobile mount in FIGS. 13 and 14 depicts environmental subject matter only and forms no part of the claimed design.

1 Claim, 14 Drawing Sheets
